Inventor
Honore Hannotte,

By his Attorneys

Edgar V. V. & Co.

UNITED STATES PATENT OFFICE.

HONORÉ HANNOTTE, OF MORSEMERE, NEW JERSEY, ASSIGNOR TO LOUIS WILKE, OF MORSEMERE, NEW JERSEY.

THEFTPROOF RECEIVER-BOX.

1,384,317.

Specification of Letters Patent. Patented July 12, 1921.

Application filed July 17, 1920. Serial No. 396,909.

To all whom it may concern:

Be it known that I, HONORÉ HANNOTTE, a citizen of Belgium, and residing at Morsemere, in the county of Bergen and State of New Jersey, have invented certain new and useful Improvements in Theftproof Receiver-Boxes, of which the following is a specification, such as will enable those skilled in the art to which it appertains to make and use the same.

This invention relates to receiver boxes particularly designed for household use and which are adapted to be placed in juxtaposition to an entrance door to a house and to be automatically locked by a member engaging such door or coöoperating with the door and the door frame, said receiver box being adapted to receive articles delivered to the house, such for example as bottles of milk, cream and the like, after which the closure member for such receiver box is moved into operative or locked position to prevent the removal of the articles placed in said receiver box until the door is opened; and the object of the invention is to provide a receiver of the class specified with a keyless lock mechanism which is retained in its operative position by the door in connection with which the receiver box is mounted when such door is in its closed position; and with this and other objects in view the invention consists in a receiver box of the class specified which is simple in construction and operation and efficient in use, and which is constructed to operate as hereinafter described and claimed.

The invention is fully disclosed in the following specification, of which the accompanying drawing forms a part, in which the separate parts of my improvement are designated by suitable reference characters in each of the views, and in which:

Figure 1 is a vertical sectional view through my improved receiver box showing the same mounted in connection with a door or door frame and indicating the method of its use;

Fig. 2 a partial section on the line 2—2 of Fig. 1; and,

Fig. 3 a partial section on the line 3—3 of Fig. 1 and on an enlarged scale.

In Figs. 1 and 2 of the drawing, I have indicated at 5 one corner portion of the hinged side of a door and at 6 the adjacent

part of the door frame which door frame is provided with an extending or overlapping strip 7, which overlaps the hinged side of the door as clearly shown in the drawing.

In practice, I provide a receiver box 8 preferably composed of sheet metal, and which, in the construction shown, is of such dimensions as to receive a bottle 9 of milk, cream or the like as shown in Fig. 1 of the drawing. The receiver box 8 is provided with a hinged cover or closure member 10 which is hinged to one side of the box 8, as shown at 11, and the opposite side 12 of the box 8 is provided at the top thereof with an inwardly directed flange 13 upon which the free end of the cover 10 is adapted to rest when said cover is in its closed position. The other side walls 14 of the box 8 are provided adjacent to the top thereof and the side wall 12, with apertures 15. A lock bolt 16 is passed transversely through the box 8 and through the apertures 15 in the side walls 14 thereof, said bolt being retained against displacement by a cotter pin or similar device 17 passed through one end portion of the bolt 16 inwardly of the side wall 14 thereof. Said end portion of the bolt is provided with an L-shaped lock arm 18 which limits the inward movement of the bolt, the part 19 of said arm extends at right angles to the bolt 16 and the part 20 of which extends at right angles to the part 19 and is adapted to be placed between the hinged side of the door 5 and the adjacent part of the door frame 6, as clearly indicated at 21 in Figs. 90 1 and 2 of the drawing.

The bolt 16 is provided centrally with an offset portion 22 which is triangular in cross section as clearly shown in Fig. 1 of the drawing. Pivoted to the inner face of the cover 10 is a downwardly directed arm 23 provided with a V-shaped recess 24 which is adapted to receive the triangular offset portion 22 of the bolt 16, as clearly shown in Figs. 1 and 3 of the drawing. The engagement of the arm 23 with the bolt 16 serves to lock the cover 10 in its closed position. The arm 23 is normally held in operative position by a spring 25 and said spring serves to permit of the inward movement of said arm in the operation of closing the cover, as hereinafter set out.

Mounted in connection with the side walls

14 of the box 8 adjacent to the side wall 12 thereof below the lock arm 18, when in its operative position, are movable stop devices 26 which, in the form of construction shown, 5 are composed of pieces of wire bent into U-shaped formation, after they have been passed through loops 27 formed in or secured to the side walls 14 of the box 8, and these stop devices serve to limit the downward movement of the lock arm 18 when 10 swung in one direction.

In the use of my improved receiver box the same is placed in position with the lock arm 18 between the door 5 and door frame 15 6 in the manner shown in Figs. 1 and 2 and with the cover 10 in its open position, and it will be noted that the part 7 of the door frame prevents the outward movement of the lock arm 18. When the article has been 20 placed in the box by the deliverer of such article, as for example the placement of the bottle 9 in the box by the milkman, the cover 10 is moved into its closed position, in which operation the arm 23 passes down over the 25 triangular offset portion 22 on the bolt 16 and springs into the position shown in Fig. 1 of the drawing through the action of the spring 25 of said arm. With the parts in their locked position, as shown in Fig. 1, it 30 will be impossible to remove the bottle 9 from the box 8 without destroying said box, until the door 5 is opened thus releasing the lock arm 18 and permitting of the swinging of said arm downwardly to release the V-shaped portion 22 of the bolt 16 from the 35 arm 23. In accomplishing this result, however, the stop device 26 in juxtaposition to the arm 18 is moved into inoperative position to permit of the downward movement 40 of the arm 18.

It will be apparent that with my improved construction, I provide a simple and yet very effective lock mechanism for the receiver box 8 without the use of keys of any 45 kind or class, and by reason of the construction of the bolt 16 and the arm 23, the bolt may be mounted in connection with the box 8 in either of two different positions, or in other words with the lock arm 18 in juxtaposition 50 with either of the side walls 14 of the box to facilitate the placement of the receiver box in connection with doors, the hinged sides of which are at the right hand or the left hand side of the door frame, and while I 55 have shown a box of specific form and construction and of specific dimensions, it will be understood that I am not necessarily limited to these details nor to the various details of the lock mechanism herein shown 60 and described, and changes therein and modifications thereof may be made, within the scope of the appended claims, without departing from the spirit of my invention or sacrificing its advantages.

65 Having fully described my invention, what

I claim as new and desire to secure by Letters Patent, is:—

1. A receiver box of the class described provided with a closure member and a lock mechanism for said closure member, said lock mechanism being provided with a part 70 adapted to be placed between a door and the door frame thereof when the door is in its closed position for retaining the lock mechanism in its operative position. 75

2. A receiver box of the class described provided with a closure member, and a keyless lock mechanism for retaining said closure member in its closed position, said lock mechanism being provided with a lock arm 80 adapted to be placed between a swinging member and the stationary support therefor to retain the lock mechanism in its operative position.

3. A receiver box of the class described 85 provided with a closure member, a lock bolt passed transversely through the receiver box and one end of which is provided outwardly of said box with a lock arm, a member carried by said closure member and adapted to operate in connection with said lock bolt to retain the closure member in its closed position, and said lock arm being adapted to be placed between a swinging member and the stationary support therefor to retain said 90 lock bolt against movement. 95

4. A receiver box of the class described provided with a closure member, a lock bolt passed transversely through the receiver 100 box and one end of which is provided outwardly of said box with an L-shaped lock arm, means for retaining the lock bolt against displacement in said receiver box, and a spring actuated member carried by 105 said closure member and adapted to operate in connection with said lock bolt to retain the closure member in its closed position.

5. A receiver box of the class described provided with a hinged cover member, a lock bolt passed transversely through the receiver 110 box and one end of which is provided outwardly of said box with an L-shaped lock arm, means for retaining the lock bolt against displacement in said receiver box, said lock bolt being provided with an offset 115 portion which is angular in form in cross section, and a spring actuated catch device pivoted to the cover member and adapted to operate in connection with the angular offset portion of said lock bolt to retain the cover 120 member in its closed position.

6. A receiver box of the class described provided with a hinged cover member, a lock bolt passed transversely through the receiver 125 box and one end of which is provided outwardly of said box with an L-shaped lock arm, means for retaining the lock bolt against displacement in said receiver box, said lock bolt being provided with an offset portion which is angular in form in cross 130

section, a spring actuated catch device pivoted to the cover member and adapted to operate in connection with the angular offset portion of said lock bolt to retain the cover member in its closed position, said lock bolt being adapted to be mounted in connection with said receiver box with the L-shaped lock arm at either side of said box, and stop devices at the sides of said receiver box and adapted to coöperate with said lock arm to hold the same against movement in one direction.

5 7. A receiver box of the class described provided with a hinged cover member, a lock bolt passed transversely through a corner portion of the receiver box and in juxtaposition to the free end portion of the cover member, means for retaining the lock bolt from displacement in said receiver box, one 10 end of said bolt being provided with a substantially L-shaped lock arm by means of which said bolt may be operated and retained against movement, said lock bolt being provided centrally thereof with an offset 15 angular portion, and a spring actuated catch device mounted in connection with the inner face of the cover member and adapted to operate in connection with the offset angular portion of the lock bolt to lock said 20 cover member in its closed position.

25 8. A receiver box of the class described provided with a hinged cover member, a lock bolt passed transversely through a corner portion of the receiver box and in juxtaposition to the free end portion of the cover member, means for retaining the lock bolt from displacement in said receiver box, one 30 end of said bolt being provided with a substantially L-shaped lock arm by means of which said bolt may be operated and re-

tained against movement, said lock bolt being provided centrally thereof with an offset angular portion, a spring actuated catch device mounted in connection with the inner face of the cover member and adapted to 45 operate in connection with the offset angular portion of the lock bolt to lock said cover member in its closed position, and a stop device adapted to coöperate with said lock arm to limit the movement thereof in one 50 direction.

9. A receiver box of the class described adapted to be placed in juxtaposition to the hinged side of a door, said receiver box being provided with a cover member, a keyless lock mechanism for locking the cover member in its closed position, and means forming a part of said lock mechanism and adapted to be placed between the hinge side of a door and the door frame for retaining 55 the lock mechanism in its operative position when the door is closed.

10. A receiver box of the class described adapted to be placed in juxtaposition to a door, said receiver box being provided with 60 a closure, and a lock mechanism for said closure, and said lock mechanism being provided with means in connection with which the door when closed operates for retaining the lock mechanism in an operative position.

In testimony that I claim the foregoing as my invention I have signed my name in presence of the subscribing witnesses this 14th day of July, 1920.

HONORÉ HANNOTTE.
